WEARING EDGE FOR SKIS

Narve Bonna, Lommedalen, near Oslo, Norway

Application July 13, 1946, Serial No. 683,371
In Norway January 21, 1943

3 Claims. (Cl. 280—11.13)

1

It is known to provide skis with wear resisting edges, using fastening pieces on which the wearing edge fits slideably with a T-shaped, trapezoid-shaped or similarly shaped dovetail groove in order that the wearing edge shall have a certain possibility of longitudinal movement relative to the ski, so that it does not reduce the flexibility of the ski to a substantial degree and nevertheless may be made without interstices. However, it has proved difficult to mount the wearing edge by sliding the same onto the fastening pieces which have been screwed onto the ski, without a foregoing division of the edge, because due to the vertical curvature of the ski and especially the usual lateral curvature of the sides of the ski, the pushing on of the wearing edge encounters a considerable and continuously increasing frictional resistance, even if the fastening pieces have been placed with great care, and as it is necessary to beat the outer end of the wearing edge, which projects behind the ski, the projecting portion of the wearing edge will bend as soon as the latter has been inserted a short distance.

This difficulty is overcome by the method according to the present invention, which consists in that the fastening pieces are at first inserted into the wearing edge and thereafter fixed to the ski by hammering. A wearing edge mounted in this manner has proved entirely satisfactory in use, because although an insertion by beating at the end of the wearing edge is very much hampered by the frictional resistance between wearing edge and fastening pieces, the resistance is not so great as to affect the flexing of the ski in a vertical plane in the mounted condition of the wearing edge.

For carrying out the invention a new form of fastening piece is afforded, as fastening pieces which both fit into a dovetail groove of the wearing edge and are suited for being fixed to the ski by hammering, have not previously been used. To permit fixation by hammering, the fastening pieces may have one or more integral nails; most conveniently they are according to the invention made substantially U-shaped, they being formed with an upright nail in either end of an elongated portion with dovetail-shaped cross section.

It may be mentioned that it is known per se to use fastening pieces which are hammered into the ski and form a dovetail guide for the wearing edge. But in the known construction the fastening pieces do not fit into a groove in the wearing edge, but inversely, and the wearing edges have a dovetail-shaped rib fitting into a recess

2

in the fastening piece. However, a fastening piece of this form will have to taper so much that when it is hammered into the ski, it is liable to break the same apart. Further, even for this known construction it has not been proposed to delay the hammering into the ski till the fastening pieces have been brought into position in the wearing edge.

The invention is illustrated in the drawings.

Fig. 1 is a lateral view of part of a wearing edge of metal with fastening pieces inserted, and

Fig. 2 is a cross sectional view of the edge and a fastening piece at an enlarged scale.

Fig. 3 is a side view of the fastening piece on an enlarged scale.

Fig. 4 is a side view of a modified form of fastening piece on an enlarged scale.

Fig. 5 is a bottom view, in small scale, of a ski with wearing edges in accordance with the invention mounted thereon.

Fig. 6 is a side view, in small scale, of the same ski shown in Fig. 5 with wearing edges mounted thereon.

Fig. 7 is a side view of the rear end portion of a ski, this view being in longitudinal cross-section and taken along the line 7—7 of Fig. 5.

Fig. 8 is a view in longitudinal section of an intermediate portion of a ski, taken along the line 8—8 of Fig. 5.

25 The metal edge 1 has a dovetail-shaped longitudinal groove 2 in the upper surface. In this groove suitably spaced fastening pieces 3 are inserted, which are substantially in the shape of a U, the rectilinear central portion 4 of which has a cross section corresponding to the groove 2 and is inserted into the same, whereas the end portions 5 project upward at a right angle and are formed as nails suited for being hammered into the ski. To effect secure fastening, the nails may 35 be formed with barbs, as shown.

The metal edge 1 may in a known manner be continuous or divided into shorter pieces, each of which may be provided with a suitable number of fastening pieces and besides be fixed immovably to the ski at one spot, for instance in the middle or in the forward end if desired. The length of the nails 5 may be adapted so that they do not wholly penetrate through the ski; they may, if desired, be of varying length in the various fastening pieces corresponding to the varying thickness of the ski. Or the nails may protrude through the ski at least in the thinnest portions of the latter and be cut off, bent or riveted on the upper side of the ski.

50 55 In the embodiment of the invention shown in

Fig. 4 and at the right hand side of Fig. 7, a modified form of the fastening piece designated by the numeral 3' is shown. In this form of the invention the fastening piece 3', which is also substantially in the shape of a U, is formed with the rectilinear central or base portion 4' which has a cross section corresponding in shape to that of the groove 2 in the wearing edge 1. The end or nail portions 5' of this fastening piece project upwardly at a right angle, as the corresponding nail portions of the form of fastening piece previously described, but these nail portions 5' of the embodiment illustrated in Fig. 4 are smooth instead of having the barbs of the embodiment shown in Figs. 1 to 3.

I claim:

1. A U-shaped fastening piece for attaching a wearing edge to a ski, comprising a straight elongated base portion with a dovetail-shaped cross-section, adapted to be slid into a dovetail groove of a wearing edge, said U-shaped fastening piece being formed at the terminal ends of said base portion with integral upright nails, said upright nails projecting from both ends of said base portion substantially at right angles thereto, said nails being adapted to be hammered into a ski.

2. A reinforcing equipment for a bottom edge of a ski, comprising a wearing edge flat on one side and dovetail-grooved longitudinally on the opposite side, a plurality of U-shaped fastening pieces, each comprising a straight elongated base portion with a dovetail-shaped cross-section, adapted to be slid into the dovetail groove of the wearing edge, and integral upright nails projecting from both ends of said base portion at the terminal portions thereof, said nails projecting substantially at right angles thereto and being adapted to be hammered into the ski.

3. On a ski having a lower edge portion, a wearing edge in abutting contact therewith, said wearing edge being mounted slidably on spaced fastening pieces covered by said wearing edge, 5 the base portion of each of said spaced fastening pieces being fitted into a longitudinally-extending groove which is dove-tail in cross-section formed in the portion of said wearing edge which abuts against said lower edge portion of said ski, 10 each of said spaced fastening pieces being of substantially U-shape form and comprising a base portion which is substantially dove-tail in cross-section and of a size such as to permit of said base portion being slid into said longitudinally-extending groove in said wearing edge, and 15 terminal upwardly-extending nail portions protruding into said ski, one nail portion extending at each terminal end of said base portion and protruding substantially at right angles to said base portion and said wearing edge.
